Primary Examiner — Ricky Pham(74) *Attorney, Agent, or Firm* — Alleman Hall McCoy
Russell & Tuttle LLP(57) **CLAIM**

The ornamental design for a grill pan, as shown and described.

DESCRIPTION

FIG. 1 is a top perspective view of a grill pan according to the present invention.

FIG. 2 is a right side view of the grill pan of FIG. 1, the left side view being a mirror image thereof.

FIG. 3 is a front view of the grill pan of FIG. 1.

FIG. 4 is a rear view of the grill pan of FIG. 1.

FIG. 5 is a top view of the grill pan of FIG. 1; and, FIG. 6 is a bottom view of the grill pan of FIG. 1.

The dashed lines illustrate a handle and a lifting tab that may be attached to the grill pan, and form no part of the claimed design.

1 Claim, 3 Drawing Sheets(56)
